CLAIM

The ornamental design for a novelty hat and megaphone, as shown.

DESCRIPTION

FIG. 1 is a front perspective view of a hat showing my new design with the human head shown in dotted lines being for illustration only;

FIG. 2 is a bottom perspective view showing the overall round shape of the hat; and,

FIG. 3 is a top view showing the hole on the top of the hat. The broken lines are for illustrative purposes only and forms no part of the claimed design.
